COIN SELECTING APPARATUS

John Gottfried, Brooklyn, N. Y., assignor to
B. & G. Coin Selectors, Incorporated, Bridge-
port, Conn.

Application March 4, 1931. Serial No. 519,980

10 Claims. (Cl. 194—101)

The present invention relates to coin selecting devices for use on coin controlled mechanisms and has for an object to provide improved apparatus for separating genuine coins from counterfeit coins and slugs. Genuine coins are uniformly made of certain metals and the other coins and slugs used for fraudulently operating coin controlled machines are made of various other materials or are of a different size from the genuine 10 coins which it is intended shall operate the mechanism. It is, therefore, possible by the use of selective devices, which affect differently coins of different sizes or coins of different metals, to separate certain selected genuine coins from various 15 other coins, counterfeit coins or slugs made of other materials.

The present invention has been developed more particularly in connection with the production of a coin separating device for use on a coin controlled mechanism designed to be operated by an American silver twenty-five cent piece, and for the purposes of illustrating the principles of the invention, such an embodiment of the invention will be more particularly described. It 25 will be understood, however, that certain features of the invention are equally applicable to devices for separating other coins.

Referring to the drawings in which is illustrated a selected embodiment of the invention— 30 Figure 1 is a somewhat diagrammatic view, partly in section, of certain operative portions of a device embodying the principles of the invention.

Fig. 2 is a sectional view taken on the line 35 2—2 of Fig. 1.

Fig. 3 is a sectional view taken on the line 3—4 of Fig. 1, showing the action of the upper ejecting spring when a twenty-five cent piece is passing through the device.

Fig. 4 is a similar sectional view taken on the line 40 3—4 but showing a smaller coin passing through the device.

Fig. 5 is a sectional view taken on the line 5—5 of Fig. 1.

Fig. 6 is a detail view showing another form 45 of ejecting mechanism, and

Fig. 7 is a view of a tell-tale device.

In the structure shown for the purposes of illustration, an upper inclined chute, or runway, 50 5 is connected directly to a lower J-shaped chute 6, a suitable portion of the length of which passes between the poles of a magnet 7. The upper inclined chute is provided with arrangements for removing under-size coins, over-size coins and 55 iron coins or slugs. A coin inserted through the

coin slot 9 rolls along the upper chute 5 past an opening 10 in the side wall of the chute, the upper edge of which opening is formed by a movable top rail 11 pivoted at 12 and arranged to be lifted by a push rod 13 extending without the casing of 60 the device. The top rail 11 carries a suitably positioned pin 15 projecting into the chute and arranged to serve as a stop for an over-size coin. In an opening 16 in the opposite side wall of the chute is carried an ejecting spring 17 designed to 65 bear lightly against a passing coin in such manner that a coin of smaller-size not engaging the top rail 11 will be immediately pressed through the opening 10, whereas a coin of the size for which the device is designed will be merely 70 pressed against the top rail, but will roll on. An over-size coin will be stopped by the pin 15 and will be ejected by the spring 17, when the push rod 13 is pressed to raise the top rail 11. A magnet 20 is provided to draw downwardly into the 75 slot 21 any coin of magnetic material, whereas coins of non-magnetic material will jump across the slot and pass to the J-shaped chute 6. This J-shaped chute is formed with the longer leg so positioned that a coin rolling down the same 80 gains a substantial velocity and the shorter leg positioned to form an upwardly inclined section up which the coin rolls as the result of its inertia.

The longer leg is preferably inclined to cause the coin to roll on its edge, so that it will gain 85 a substantial speed of rotation during its downward movement and the shorter leg is inclined upwardly to the point of discharge.

The magnet 7 is preferably positioned adjacent the upwardly inclined section constituting the 90 shorter leg of the J-shaped section and its magnetic strength is so related to the inclination of the two sections of the J-shaped chute and the velocity of a coin rolling therein that silver coins will be discharged at the upper end of this inclined section, but with a very low velocity thereby to drop into the coin chute 25, while other coins of less electrical conductivity will pass over by a longer path to the coin chute 26 from whence they will be returned, and coins of greater electrical conductivity, such, for example, as copper and aluminum, will be still more retarded and 95 will not pass out of the chute at the discharge end, but will roll backwardly.

Suitable provision is made for removing the 105 coins or slugs which roll back. In the structure shown in Fig. 1, a lateral opening 28 is provided in the side of the chute, preferably at the lowermost point, and a spring deflector 30 is positioned to engage the backwardly rolling coin and de- 110

- flect it through said lateral opening. The spring 30 is very flexible and is easily pressed outwardly by a passing coin as said coin engages the diagonally inwardly extending end of said spring. 5 After the coin passes the end of the spring, it snaps back to original position and during the backward movement of the coin serves as a deflector to tip the coin out through the lateral opening 28 and into the chute 31, whence it is returned as a rejected coin.
- 10 An alternative arrangement for ejecting the coin which rolls back is illustrated in Fig. 6. In this arrangement the coin in its rolled back position can be ejected by the spring pressed push pin 35. This push pin may obviously be connected with any operative part, such, for example, as the operating mechanism for ejecting an article in an automatic vending machine to which the device may be attached.
- 15 As best shown in Fig. 5, the magnet 7 may be provided with iron pole pieces 36 suitably fitted into holes in the side walls of the upwardly inclined section of the chute in order that a strong concentrated magnetic field may be provided.
- 20 Ordinarily the side walls of the J-shaped chute need not be specially formed to prevent the rolling coin hitting against the forward edge of the opening.
- 25 It is desirable to provide means whereby in the event a spurious coin passes through the machine, a signal will be given which will be observable to an operator, in order that attempts to rob the machine may be detected at the time of the attempt. Such a device is shown in Fig. 30 7 of the drawings and comprises a scale pan 40 positioned to be moved by the spurious coin to close an electric circuit which, in turn, may be connected to flash an electric light or other signal.
- 35 In the arrangement shown the tell-tale device 40 is connected in the path of the chute 25. A coin falling in said chute strikes an anvil 41, which serves as an additional selecting device, as a check on coins which have passed through the magnetic field and have been selected as good coins. The silver coin will bounce a substantial distance to the chute 42, but lead coins will drop in the chute 43 and strike the scale pan 40 moving it about pivot 45. The electric contact finger 46 will wipe against the contact 47 to operate the tell-tale signal.
- 40 The arrangement may, furthermore, be such that the coins from the chutes 26 and 31 will be delivered into the chute 43 so that discarded coins from these chutes will also operate the tell-tale.
- 45 The foregoing particular description is illustrative merely and is not intended as defining the limits of the invention.
- 50 I claim:—
1. In a coin selecting device, in combination, a chute having a downwardly inclined section down which a coin may roll by gravity and an upwardly inclined section up which the coin may roll by its inertia to a point of discharge, and a magnet adjacent the upwardly inclined section for creating a magnetic field to retard a coin more or less according to the electrical conductivity of the material of the coin, whereby coins of certain character will be retarded sufficiently to roll back, provision being made for the discharge of the backwardly rolling coin from the coin chute.
  2. In a coin selecting device, in combination, 55 a chute having a downwardly inclined section
- down which a coin may roll by gravity and an upwardly inclined section up which the coin may roll by its inertia to a point of discharge, a magnet adjacent said chute for creating a magnetic field to retard a coin rolling in the chute more or less according to the electrical conductivity of the material of the coin, whereby coins of certain character will be retarded sufficiently to prevent their rolling to the point of discharge and means for ejecting a coin which fails to reach the point of discharge. 80
3. In a coin selecting device, in combination, a chute having a downwardly inclined section down which a coin may roll by gravity and an upwardly inclined section up which the coin may roll by its inertia to a point of discharge, a magnet adjacent said chute for creating a magnetic field to retard a coin rolling in the chute more or less according to the electrical conductivity of the material of the coin, the strength of the magnet being so related to the length and inclination of the chute sections that a silver twenty-five cent piece will roll along the chute through the magnetic field to the point of discharge, but a copper coin of the same size will stop short of the point of discharge and roll backward, provision being made for the discharge of the backward rolling coin from the coin chute. 85
4. In a coin selecting device, in combination, a chute having a downwardly inclined section down which a coin may roll by gravity and an upwardly inclined section up which the coin may roll by its inertia to a point of discharge, a magnet adjacent said chute for creating a magnetic field to retard a coin rolling in the chute more or less according to the electrical conductivity of the material of the coin, the strength of the magnet being so related to the length and inclination of the chute sections that a silver twenty-five cent piece will roll along the chute through the magnetic field to the point of discharge, but a copper coin of the same size will stop short of the point of discharge and roll backward, provision being made for the discharge of the backward rolling coin from the coin chute. 90
5. In a coin selecting device, in combination, a J-shaped coin chute positioned in a substantially vertical plane to permit a coin to roll down the longer leg and up the shorter leg to a point of discharge, said chute being provided with a lateral opening at its lower portion, a spring deflector adjacent said opening movable to permit forward passage of a coin but engageable with a backwardly rolling coin to deflect it through the opening, and a magnet positioned to provide a magnetic field at the shorter leg 100 of the chute to retard a coin more or less according to its electrical conductivity, whereby coins of certain character will be retarded sufficiently to roll back and be discharged through the lateral opening. 105
6. In a coin selecting device, in combination, a J-shaped coin chute positioned in a substantially vertical plane to permit a coin to roll down the longer leg and up the shorter leg to a point of discharge, said chute being provided with an opening at its lower portion, a magnet positioned adjacent the shorter leg of the chute to provide a magnetic field to retard a coin more or less according to its electrical conductivity, whereby copper coins will be retarded sufficiently to roll 110

- back before reaching the point of discharge and means for ejecting a rolled back coin through said opening.
7. In a coin selecting device, in combination, an upwardly inclined chute section, means for rolling a coin up said chute at a predetermined velocity, a magnet adjacent said chute for creating a magnetic field across said chute section to retard a coin more or less according to the electrical conductivity of the material of the coin, the strength of the magnet being so related to the predetermined velocity of the coin and the length and inclination of the chute section that a silver coin will roll through the magnetic field to the point of discharge, but coins having greater electrical conductivity such as copper will be retarded sufficiently to roll back before reaching the point of discharge.
8. In a coin selecting device, in combination, an inclined coin chute provided with a movable top rail to form a guideway for coins, a J-shaped coin chute connected to said inclined chute to receive coins therefrom, said J-shaped coin chute having one section down which coins roll under the influence of gravity and a second upwardly inclined section up which coins roll as the result of inertia, and a magnet adjacent the upwardly inclined section for creating a magnetic field to retard a coin more or less according to the electrical conductivity of the material of the coin, whereby coins of certain character will be retarded sufficiently to roll back while coins of certain other character will roll forward to the point of discharge, and a spring pressed push pin positioned to be projected to eject laterally from the coin chute coins which have rolled backwardly to the lowermost point.
9. In a coin selecting device, in combination, an inclined coin chute provided with a movable top rail to form a guideway for coins, a J-shaped coin chute connected to said inclined chute to receive coins therefrom, said J-shaped coin chute having one section down which coins roll under the influence of gravity and a second upwardly inclined section up which coins roll as the result of inertia, a magnet adjacent the upwardly inclined section for creating a magnetic field to retard a coin more or less according to the electrical conductivity of the material of the coin, whereby coins of certain character will be retarded sufficiently to roll back while coins of certain other character will roll forward to the point of discharge, and a spring pressed push pin positioned to be projected to eject laterally from the coin chute coins which have rolled backwardly to the lowermost point.
10. In a coin selecting device, in combination, a J-shaped coin chute arranged to project a coin in general horizontally but slightly upwardly, a magnet positioned to provide a magnetic field which will retard the movement of the coin so far as its horizontal component of movement is concerned, substantially as described.
